FIG. 1 is a perspective view of a solarium embodying my new design;

FIG. 2 is a side elevational view of the solarium shown in FIG. 1;

FIG. 3 is a cross sectional view taken along line 3—3 of FIG. 2 looking in the direction of the arrows;

FIG. 4 is a cross sectional view taken along line 4—4 of FIG. 2 looking in the direction of the arrows;

FIG. 5 is a perspective view of a modified embodiment of the solarium shown in FIG. 1;

FIG. 6 is a side elevational view of the solarium shown in FIG. 5;

FIG. 7 is a cross sectional view taken along line 7—7 of FIG. 6 looking in the direction of the arrows;

FIG. 8 is a cross sectional view taken along line 8—8 of FIG. 6 looking in the direction of the arrows;

FIG. 9 is a perspective view of a further modified embodiment of the solarium shown in FIG. 1;

FIG. 10 is a side elevational view of the solarium shown in FIG. 9;

FIG. 11 is a top plan view of the solarium shown in FIG. 9;

FIG. 12 is an end elevational view of the solarium shown in FIG. 9;

FIG. 13 is a perspective view of still another modified form of the embodiment shown in FIG. 1;

FIG. 14 is a side elevational view of the solarium shown in FIG. 13;

FIG. 15 is a top plan view of the solarium shown in FIG. 14; and

FIG. 16 is a front elevational view of the solarium shown in FIG. 1, the rear end elevational view being similar.

This is a continuation of design applications Ser. Nos. D. 86,817, filed Sept. 3, 1965; D. 86,834, filed Sept. 3, 1965; D. 86,845, filed Sept. 3, 1965; and D. 86,848, filed Sept. 3, 1965 and now abandoned.

I claim:

The ornamental design for a solarium, as shown and described.
